Des. 137

Nathaniel Batcheler, New York, New York,
Letters Patent Design No. 137, dated 24th July 1844

The schedule referred to in these Letters Patent and making
part of the same.

To all whom it may concern: Be it known that I, Nathaniel Batcheler of New York, in the County of New York and State of New York, have produced a new Design for an ornamental "Clock frame" and I do hereby declare the following to be a full, clear and exact Description of the same reference being had to the annexed Drawings, making a part of this Specification, in which

Fig. 1. is front elevation showing the special ornaments making this design or configuration

I make a frame consisting of one piece forming a top, two sides and feet without any special ornaments, and a front or face of frame ornamented in the modern French Style of Architecture.

The configuration, consists in a special lead moulding (a) at the top followed by a dead flat, and in continuation a raised moulding with a receding base flanking upon a flat ground surface. The centre of this ground is an opening to show the face of the clock, and this is surrounded with light beading which is again surrounded by scroll work, this surmounts upon a base of Egyptian scroll leaves, forming a moulding which is expanded by a line of concave fluting upon which is intended a plain square moulding (b)

Below this, forming the bottom and feet, is a line of leafage and scrolls extending from side to side as (c) it figures as placed in the drawing may be set on top, but I do not claim this in combination.

What I claim as my production and desire to secure by Letters Patent is the ornamental configuration of a clock frame, to be cast in metal as described and set forth herein.
